UNITED STATES PATENT OFFICE.

ARTHUR D. PRATT, OF NEW YORK, N. Y., ASSIGNOR TO THE BABCOCK & WILCOX COMPANY, OF BAYONNE, NEW JERSEY, A CORPORATION OF NEW JERSEY.

WATER-TUBE BOILER.

Application filed October 16, 1919. Serial No. 330,946.

To all whom it may concern:

Be it known that I, ARTHUR D. PRATT, a citizen of the United States, residing in the city of New York, borough of Manhattan, county and State of New York, have invented certain new and useful Improvements in Water-Tube Boilers, of which the following is a specification.

My invention relates to a water tube boiler especially designed for use where there are large quantities of dust in the gases, and particularly an arrangement by which the baffles and tubes in such a boiler may be relieved of the accumulation of dust which will collect thereon. In the drawings, Figure 1 is a side elevation partly in section of a boiler embodying one form of my invention; Fig. 2 is a side elevation, of the exterior of the furnace illustrated in Fig. 1, with some 20 of the side wall broken away; Fig. 3 is a section on the line 3—3 of Fig. 2; Fig. 4 is a side view, partly in section, of the movable baffles; and Fig. 5 is a side view of the movable baffles. Similar reference numerals indicate similar parts in the several views.

The boiler illustrated comprises two transverse steam and water drums 1 and 2 and a transverse mud drum 3, set parallel and connected by banks of tubes 4 and 5. The upper drums are connected by steam circulators 6 and water circulators 7. The latter support tiling which forms a roof over the cross passages from the uptake to the downtake and prevents the gases from striking the drums above the water line. Each bank is shown as having five rows of tubes, the upper ends of which are straight and are expanded into a stepped tube sheet, and the lower ends curved to properly enter a circular mud drum. Two additional rows of vertical tubes 8 and 9 connect the mud drum with the upper drums, these two rows forming a central bank. A baffle wall 10 is built in the space between the rows of tubes 8 and 9, the tubes forming a support for the wall which extends upwardly from the mud drum to such height as to leave ample space for the products of combustion to travel from the front to the rear pass. The wall 10 is accessible for repairs through the doors 20, there being ample room for a man to work between the banks of tubes.

The vertical baffle wall 10 is located centrally between the main banks of tubes. Projecting from said baffle wall to the main

banks of tubes are cross baffles 11, preferably of cast iron. A similar baffle 12 is located between the bank of tubes 5 and the rear wall of the setting. As one means by which the baffles 11 and 12 may be turned or shifted to remove the accumulated dust, I have shown them as mounted upon shafts 121 which extend through openings in the side walls of the setting. In the preferred form which I have chosen for purposes of illustration, the shafts 121 are provided with weights 122 arranged to hold the baffle normally in operative position.

Suitable dusting doors 14 are provided through which an air or steam lance may be introduced for blowing the accumulated dust from the surfaces of the tubes and also from the surface of the mud drum. Hoppers 15 may be placed under the setting to receive the deposits. Any dust deposited upon the baffles 11 and 12 may be readily discharged therefrom by turning or shifting the baffles, and the accumulation upon the tubes and the mud drum removed by an air or steam lance.

The boiler may be fired by any suitable furnaces, indicated at 16. The gases enter the lower part of the front bank of tubes 4, flow in a general upward direction over said tubes, thence across above the baffle wall 10 and in a general downward direction over the tubes of bank 5. The baffles 11 and 12 cause the gases, in their general flow, to cross and recross the banks of tubes as indicated by the arrows. The gases finally escape through the outlet 17. A seal 18 between the wall 19 and the lower drum, prevents short circuiting of the gases.

The main steam outlet 21 is placed at the top and centre of the rear steam and water drum. A feed water connection 22 discharges into a trough in the rear drum and from which the water is distributed to the drum.

The described boiler may be used as a waste heat boiler, and is especially adapted for use in connection with processes where the gases carry a large amount of dust, such as results in the volatile concentration of zinc refuse from zinc oxide furnaces. In such cases, any substantial accumulation of the dust carried by the gases may be gotten rid of at frequent intervals by rotating the cross baffles 11 and 12 and removing the accumulation from the surfaces of the tubes by an air or steam lance. Because of the large

amount of dust in the gases, the tubes 4 and 5 will also become coated, so that it is necessary to provide some means by which this dust or deposit may be readily removed from them. To this end, I have provided scrapers 23 on each bank of tubes together with means by which they may be moved along the tubes to remove the deposits. In order that these scrapers shall be most effective, I prefer to arrange the tubes as shown in Figure 1 with their upper ends straight and vertical so as to enable the scrapers to operate up to the point where the tubes enter the upper drums 1 and 2. To this end, I preferably provide a stepped tube sheet for the upper drums, though it is obvious that any other form of tube sheet which will permit the bank of tubes to enter the drum without curving the tubes, will answer my purposes.

As shown in Figure 1, the lower drum 3 is out of vertical alinement with the upper drums and by making the tubes 4 and 5 vertical and straight throughout a greater portion of their length, beginning at the upper drums and by curving the lower portions only in order to connect the tubes into the lower drum, I provide an arrangement by which the scrapers 23 may operate over the greater portion of the length of the tubes and, at the same time, by reason of the curvature at the bottom of the tubes, the dust removed by the scrapers 23 will fall away from the drum 3 into the hoppers 15.

The scrapers 23 may be of any suitable construction and, in the form illustrated, comprise cylindrical members 40 made in two or three parts surrounding each of the tubes, these cylindrical members having projections which engage between the plates of a frame 30 to ears 31 of which are attached chains passing over chain wheels 32, 33, 34 and 35, the corresponding chain wheels on either side of the setting being connected by suitable shafts, and the whole system of shafts and wheels being turned, in the form illustrated, through suitable gearing by a motor 37.

As will be seen by an inspection of Figure 1, the two sets of scrapers counterbalance each other; that is to say, when one is at the top of the tubes, the other is at the bottom. Rotation of the shaft of the motor 37, first in one direction and then the other, will move the scrapers up and down the tubes to clean off the deposit and dust. In their upward travel, the scrapers move up to the upper drums 1 and 2.

The arrangement of the cylindrical members 40 and the frame 30 supporting them is such as to permit the removal of any of the cylindrical members or the frame without disturbing the tubes with which they cooperate.

If desired, the scrapers 23 may be kept

in continuous motion while the boiler is in operation. To this end, in the form illustrated, one of the chains connected to the scrapers is provided with a pair of members 371 and 372, arranged to contact alternately with a switch lever 38. The switch serves to reverse the motor 37. By this means, the switch lever is moved and the motor reversed as each scraper alternately reaches the limit of its upward stroke. Any other form of scraper moving means may be used, such as hand-operated chains, or the switch 38 may be thrown by hand.

Preferably, the baffles 11 and 12 are made to extend closely to the tubes 5 and 6. Unless provision were made for it, this would prevent the passage of the scrapers 23. To permit this, I arrange the scraper frames and the baffles so that contact between the two will serve to tilt the baffle to permit the scrapers to pass, in the manner shown in Fig. 2. As soon as the scraper has passed, weight 122 will return the baffle to normal position. The arrangement I have shown for this purpose is extremely simple, but obviously any suitable form of baffle operating device may be used.

While I have illustrated my invention in connection with a steam boiler, it will be understood that many of its parts may be applied also to any other form of water heater such as the economizer portion of a boiler and it will be understood that the term "boiler" as used in the appended claims refers not only to a boiler proper but also to the economizer portion of a boiler.

What I claim and desire to secure by Letters Patent of the United States is:—

1. A boiler having part of its heating surface formed of vertically-extending straight tubes with laterally curved lower portions, and scrapers permanently mounted upon the tubes and arranged to scrape the surfaces of their straight portions, the curvature of the tubes being such as to permit the soot thus scraped off to drop away between the lower parts of the tubes, and movable baffles having a portion thereof normally located in the path of movement of the scrapers, and adapted to be contacted by the scrapers to be moved out of the path of the scrapers.

2. A water tube boiler having a set of permanently mounted scrapers engaging the straight portions of some of its water tubes, means to reciprocate the scrapers, and a baffle having a portion thereof in the path of the scrapers, said baffle being arranged to be moved by the motion of the scrapers to permit the scrapers to pass the baffle when the scrapers are moved in either direction.

3. A boiler having a vertical flue and a bank of tubes extending lengthwise of the tubes, a baffle extending from the wall of the flue to the outermost of the tubes,

scrapers surrounding the outermost tubes and arranged to be moved up and down thereon, said baffle being arranged to be moved by the motion of the scrapers to permit the scrapers to pass the baffle when the scrapers are moved in either direction.

4. A boiler having a vertical flue and a bank of tubes extending lengthwise of the tubes, a baffle extending from the wall of

the flue to the outermost of the tubes, scrapers surrounding the outermost tubes and arranged to be moved up and down thereon, said baffle being pivotally mounted and arranged to be held normally in operative position by gravity and to be moved out of 15 normal position by the scrapers.

ARTHUR D. PRATT.
